UNITED STATES PATENT OFFICE

2,490,101

ROCKET TYPE WEAPON

Robert B. Staver, Portland, Oreg.

Application April 8, 1947, Serial No. 740,034

7 Claims. (Cl. 102—49)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to an improvement in rocket type weapons and more particularly to a structure wherein the launcher tube for a rocket projectile is utilized as the motor chamber thereof.

More particularly, it is an object of the invention to provide a rocket projectile capable of being manufactured much more economically than projectiles of the same size and of the type now in use, and which can be readily assembled just prior to firing to thereby enable the component parts of the projectile to be stored and transported in a much more compact manner than is possible with the conventional rocket projectiles.

Still another further aim of the invention is to provide a structure whereby the weight of the projectile is materially reduced without effecting the size of the bursting charge thereof.

A further object of the invention is to provide a projectile having a novel form of tail fin assembly a part of which functions in conjunction with the launcher tube to provide the propelling nozzle of the projectile.

Other objects and advantages of the invention will hereinafter become more fully apparent from the following description of the drawing, which illustrates a preferred embodiment thereof, and wherein:

Figure 1 is a view partly in longitudinal section, partly in side elevation and partly diagrammatic; and

Figure 2 is an end view in elevation looking toward the rear end of the launcher tube containing the projectile.

Referring more particularly to the drawing, wherein like reference characters designate like or corresponding parts throughout the several views, 3 designates generally a rocket launcher tube which may be of any suitable construction such as the 2.36 inch A. T. rocket launcher M1A1 and which includes an electrical system 4 which may be of any suitable arrangement such as that provided for the aforementioned rocket launcher.

The rocket projectile, designated generally 5, includes a head 6 of conventional construction and design which is provided with a rearwardly extending internally threaded socket 7. A tube or rod 8 is connected to or formed integral with a tail fin assembly, designated generally 9, at one of its ends. The tail fin assembly 9 includes a body portion 10 which is substantially semi-

2

elliptical in longitudinal contour and to the enlarged end of which the rod 8 is connected. The assembly 9 also includes a plurality of fins 11 which project radially from the body 10. The opposite end 12 of the rod 8 is threaded to detachably engage in the socket 7. A propelling charge in the form of a powder stick 13 having a bore 14 sized to encompass the rod 8 is mounted thereon and bears against the body 10, at one end thereof, and against the socket 7, at its opposite end. The powder stick 13 is preferably of laminated construction being formed of a plurality of disks 15 assembled in abutting relationship. Said powder stick 13 is of a quick burning composition for a purpose which will hereinafter become apparent.

The projectile 5 is inserted in the rear end of the launcher tube 3 in a conventional manner and may be connected to the electrical propelling charge igniting system 4 in the same manner that a 2.36 inch rocket is connected to the igniting means of the launcher M1A1. The head of the rocket is provided with an obturating band 16 which is secured thereto and which bears against the wall of the bore 17 of the launcher 3. The band 16 is preferably formed of copper. The outer edges of the fins 11 slidably engage the wall of the bore 17 to combine with the obturating band 16 for guiding the projectile 5 in its movement through the tube 3. Assuming that the igniting means 4 has been energized by closing the switch 18 thereof, the propelling charge 13 will be ignited thereby and due to its quick burning characteristics will burn very rapidly and be consumed before the projectile 5 has completed its travel through tube 3. The propelling gases produced by the burning of the charge 13 will be confined in the motor chamber formed by the portion of the tube bore 17 which surrounds the charge 13. Escape of these compressed gases forwardly and around the head 6 will be prevented by the band 16 so that said gases will pass rearwardly through the tube 3 and between said tube and the body portion 10. The rearwardly tapered shape of the body portion 10 functions in conjunction with the wall of the tube bore 17 which is in encompassing relationship thereto to form an annular nozzle for the projectile 5 to cause the projectile to be propelled thereby forwardly through the tube 3, or to the left as seen in Figure 1. Due to the fast burning of the charge 13 the projectile 5 will be characterized by very rapid acceleration as the entire propelling force thereof will be obtained during movement of the projectile through the

tube 3, so that its maximum velocity will be acquired adjacent the muzzle of the tube.

Obviously, if desired, bore 17 could be rifled and the band 16 then utilized as a rotating band.

From the foregoing it will be readily apparent that the projectile 5 is capable of being much more economically manufactured than conventional rocket projectiles having motor chambers as a component part of the projectile; and as the charge 13 can be assembled on the rod 8 and the rod 8 and tail fin assembly 9 thereafter and very readily attached to the head 6, it will be obvious that the projectile 5 can be packed very compactly for storage and transportation.

It is to be understood that only a very simple embodiment of the invention has been disclosed and that rocket projectiles constructed in accordance with the principles herein disclosed may be made of any desired size or shape. Various other modifications and changes are likewise contemplated and may obviously be resorted to without departing from the spirit and scope of the invention as hereinafter defined by the appended claims.

I claim:

1. A rocket type weapon comprising a projectile having a head, an elongated member connected to the projectile head and extending rearwardly therefrom, an enlargement on the rear end of the member having radially projecting fins, a launcher tube for slidably receiving the projectile, and a powder stick supported on the elongated member and forming the propelling charge of the projectile, the portion of the launcher tube surrounding the powder stick forming the motor chamber, and said enlargement and the surrounding portion of the tube forming the nozzle.

2. A rocket type weapon as in claim 1, said projectile head having an obturating band encompassing a portion thereof and in engagement with the bore of the tube.

3. A rocket type weapon comprising a projectile having a propelling charge externally mounted thereon, and a tube for launching the projectile, said tube functioning as a motor chamber for the propelling charge during travel of the projectile therethrough, said projectile hav-

ing a tail fin assembly including a body portion disposed behind the propelling charge, said body portion being constructed to cooperate with the tube to form a nozzle.

5. A chamberless rocket type projectile comprising a forwardly disposed payload-carrying head, an elongated member connected to said head and extending rearwardly therefrom, an enlargement of circular transverse cross section 10 on the rear end of said member, said enlargement diminishing in transverse cross section toward the rear to define an annular rocket nozzle when said projectile is placed in a launching tube, a plurality of radial fins projecting from said enlargement to a radius slightly greater than the maximum diameter of said enlargement to maintain said enlargement centered when the rocket is placed in a launching tube, and a propellant charge supported on the elongated member, the 15 maximum radial dimension of said charge from the axis of said member being no greater than the maximum radial extent of said fins.

6. The invention cited in claim 4 including an obturating band about said rocket head.

7. The invention cited in claim 5 wherein said propellant charge is an annular member disposed about said elongated member.

8. The invention cited in claim 6 wherein said annular member has a rearwardly diminishing cross section to provide an increasing free port area toward the rear.

ROBERT B. STAVER.
